(57) **CLAIM**

We claim the ornamental design for a printed circuit board daughter board support, as shown and described.

DESCRIPTION

FIG. 1 is a side elevational perspective view of a printed circuit board daughter board support;

FIG. 2 is a front elevational view of a printed circuit board daughter board support shown on a reduced scale;

FIG. 3 is a rear elevational view of a printed circuit board daughter board support shown on a reduced scale;

FIG. 4 is a side elevational view of one side of a printed circuit board daughter board support;

FIG. 5 is a side elevational view of the opposite side of a printed circuit board daughter board support;

FIG. 6 is a top view of a printed circuit board daughter board support; and,

FIG. 7 is a bottom view of a printed circuit board daughter board support.
